Specification for Design.

Patented Mar. 7, 1922.

Application filed July 30, 1919. Serial No. 314,350. Term of patent 14 years.

To all whom it may concern:

Be it known that I, PEARL N. JONES, a citizen of the United States, residing at Pittsburgh, in the county of Allegheny and State of Pennsylvania, have invented a new, original, and ornamental Design for Fare Tokens, of which the following is a specification, reference being had to the accompanying drawing, forming part thereof, in which:—

Figure 1 is a front view of a fare token embodying my new design; and

Figure 2 is a back view of the same. The fare token herein disclosed comprises a metal annulus enclosing a letter P joined to the annulus throughout the major portion of the loop and at the base.

I claim:

The ornamental design for a fare token, as shown and described.

In testimony whereof, I have hereunto set my hand.

PEARL N. JONES.
